United States Patent Office

Des. 195,879
Patented Aug. 6, 1963

195,879

LATCH HANDLE OR SIMILAR ARTICLE

Peter P. Klepa, Los Angeles, Calif., assignor to Electronic Enclosures, Inc., Los Angeles, Calif., a corporation of California

Filed Oct. 25, 1962, Ser. No. 72,264

Term of patent 14 years

(Cl. D50—5)

FIG. 1 is an isometric view of a latch handle showing my new design;

FIG. 2 is a front view;

FIG. 3 is a side view;

FIG. 4 is a rear view;

FIG. 5 is a top plan view; and

FIG. 6 is a bottom view thereof.

I claim:

The ornamental design for a latch handle or similar article, substantially as shown.
